Attorney

UNITED STATES PATENT OFFICE.

FRANK M. EDGAR AND THOMAS P. ARCHER, OF DETROIT, MICHIGAN, ASSIGNORS TO TERNSTEDT MANUFACTURING COMPANY, OF DETROIT, MICHIGAN, A CORPORATION OF MICHIGAN.

LOCK.

Application filed June 22, 1923. Serial No. 647,128.

To all whom it may concern:

Be it known that FRANK M. EDGAR and THOMAS P. ARCHER, citizens of the United States, residing at Detroit, in the county of Wayne and State of Michigan, have invented certain new and useful Improvements in Locks, of which the following is a specification.

This invention relates to locks and more particularly to automobile locks of the type provided with a vertical rotary spindle.

The locks now on the market, have a sliding bolt construction which sometimes catches on the guide members struck down from the cover plate, preventing the sliding bolt from being retracted. One of the objects of the present invention is to so construct the sliding bolt that it is guided by the tongues struck down from the cover plate during its entire movement.

A further object is to provide means for holding in place the spring for shooting the bolt, and to prevent the same from jumping up, thereby becoming disengaged from the sliding bolt.

Another object is to provide an improved chair construction for the sliding bolt which is cheaper to build and more easily assembled.

In the drawings:

Fig. 1 is a plan view of the lock.

Fig. 2 is a section on the line 2—2 of Fig. 1 showing the means for guiding the sliding bolt.

Fig. 3 is a section on the line 3—3 of Fig. 1 showing the spring retaining means.

Fig. 4 is a detail in perspective of the sliding bolt.

The lock consists of a face plate *a*, a front plate *b* and a cover plate *c*. A vertical rotary spindle *d* is mounted in bearings *e* carried by the front plate and the central portion of the spindle is bent as shown for the purpose of engaging the sliding bolt in a manner later to be described. The sliding bolt is provided with the usual lug *f*, and the roll back *g* mounted in the front plate is adapted to engage the lug *f* for retracting the bolt. A thumb turn *h* actuates the dogging member *i* for dogging the roll back.

The inner end of the sliding bolt is provided with turned up sides *k* a portion of said turned up sides being of a greater height than the rest so as to abut the side of the angle bar *m* which is riveted as at *n* to the

face of the sliding bolt *x*. This provides an improved chair construction which can be more easily made and assembled than that of the prior art. The bent middle portion of the spindle is adapted to engage this chair portion whereby rotation of the spindle will cause the sliding bolt to be retracted.

The cover plate *c* is provided with a pair of down-turned ears *o* which are adapted to slidably contact with the outer surfaces of the up-turned sides *k* of the sliding bolt for the purpose of guiding the same. Since the up-turned sides of the sliding bolt are in engagement with the guiding ears during the entire movement of said sliding bolt, there is no tendency for the down-turned guiding ears to obstruct the free retraction of the sliding bolt.

A spiral spring *p* carried by the front plate is adapted to engage the end of the sliding bolt for forcing the same outwardly. To prevent this spring from becoming disengaged from the end of the sliding bolt, a portion of the cover plate designated *q* is depressed as shown in Fig. 3 for the purpose of holding the spring in place.

This construction is easily assembled and it overcomes the objectional features of the other locks which sometimes cause serious difficulty in their operation.

What we claim is:

1. In a lock, the combination of a cover plate, a sliding bolt, means adapted to engage the sliding bolt for the purpose of retracting the same, the inner end of the bolt provided with raised bearing surfaces and ears struck down from the cover plate adapted to engage the bearing surfaces of the bolt for the purpose of guiding the same.

2. In a lock, the combination of a cover plate, a sliding bolt, means for retracting the same, the inner end of the sliding bolt provided with turned up edges forming side walls, and ears struck down from the cover plate for engaging said side walls to guide the sliding bolt.

3. In a lock, the combination of a cover plate, a sliding bolt, a spring adapted to engage the sliding bolt for forcing the same outwardly, and a depressed rib portion carried by the cover plate adapted to bear on the spring for holding the same in place.

4. In a lock, the combination of a cover plate, a sliding bolt, a spring adapted to engage the sliding bolt for forcing the same

outwardly, and an elongated rib depressed from the cover plate and adapted to bear on the spring to prevent the same from becoming disengaged from the sliding bolt.

5. In a lock, the combination of a cover plate, a sliding bolt, means for retracting the same, the inner end of the sliding bolt provided with turned up edges forming side walls, a portion of said side walls being cut 10 away and slidably guided under the cover plate, and ears struck down from the cover plate for engaging said side walls to also guide the sliding bolt.

6. In a lock, the combination of a cover 15 plate provided with a central opening, a sliding bolt, means for retracting the same, the inner end of said sliding bolt provided

with turned up edges forming side walls, a portion of which project through the opening in the cover plate and the remaining 20 portion of said side walls slidably guided under the cover plate, and ears struck down from the cover plate for engaging said side walls to guide the sliding bolt, that portion of the side walls projecting through the 25 opening adapted to engage the edge of the opening in the cover plate for the purpose of limiting the retracting movement of said sliding bolt.

In testimony whereof we affix our signatures. 30

FRANK M. EDGAR.
THOMAS P. ARCHER.
